The ornamental design for a soldering tip, as shown and described.

DESCRIPTION

FIG. 1 is a perspective view of a soldering tip showing a first embodiment of our new design;

FIG. 2 is a front view thereof, the opposite side being a mirror image of the side shown herein;

FIG. 3 is a left side view thereof;

FIG. 4 is a right side view thereof;

FIG. 5 is a top view thereof;

FIG. 6 is a bottom view thereof;

FIG. 7 is a perspective view of a soldering tip showing a second embodiment of our new design;

FIG. 8 is a front view thereof, the opposite side being a mirror image of the side shown herein;

FIG. 9 is a left side view thereof;

FIG. 10 is a right side view thereof;

FIG. 11 is a top view thereof; and,

FIG. 12 is a bottom view thereof.

The portion of the soldering tip shown in broken lines is for illustrative purposes only and forms no part of the claim. The dashed-dot lines show a borderline between the claimed design and unclaimed subject matter.
